UNITED STATES PATENT OFFICE.

EDMUND S. HUNT, OF WEYMOUTH, MASSACHUSETTS.

FIRE-WORKS.

SPECIFICATION forming part of Letters Patent No. 229,890, dated July 13, 1880.

Application filed May 27, 1880. (No model.)

To all whom it may concern:

Be it known that I, EDMUND S. HUNT, of Weymouth, in the county of Norfolk and State of Massachusetts, have invented a new and useful Improvement in Fire-Works, of which the following is a full, clear, concise, and exact description, reference being had to the accompanying drawings, making a part hereof.

My invention relates to that class of fire-works commonly called "sun-wheels," the smaller sorts of which are also known as "pin-wheels;" and it consists in securing a short piece of lance-work in a radial slot in the disk which supports the coiled case which contains the driving-charge.

In the drawings, Figure 1 is a plan. Fig. 2 is a section on line xx of Fig. 1.

A is a disk of pasteboard or the like, with a hole through it at its center for the pin on which the wheel revolves.

B is the lance-work, consisting of a short case filled with a composition, b , to produce a colored flame.

C is the driving-case, filled with a composition, c , to produce colored flame, and also to cause the wheel to revolve on its pin.

The outer end of the case B is open, and a hole, c' , is pressed through case C, so that when case C is secured to the periphery of disk A this hole c' will be over the mouth of case B, the purpose being to insure the ignition of the filling b in case B when the filling c of case C has burned as far as the hole c' .

What I claim as my invention is—

In combination, disk A, with the radial slot, the case B, with its filling b , secured in that slot and open at the outer end, and the coiled case C, with its filling c , and having the hole c' through it at the mouth of the case B, substantially as described.

EDMUND S. HUNT.
